UNITED STATES PATENT OFFICE.

WILLIAM H. SCOTT, OF ST. LOUIS, MISSOURI, ASSIGNOR TO THE CONTROLLER COMPANY OF AMERICA, OF ST. LOUIS, MISSOURI, A CORPORATION OF MISSOURI.

TELEPHONE-LOCK.

SPECIFICATION forming part of Letters Patent No. 728,994, dated May 26, 1903.

Application filed June 25, 1902. Serial No. 113,113. (No model.)

To all whom it may concern:

Be it known that I, WILLIAM H. SCOTT, a citizen of the United States, residing at St. Louis, Missouri, have invented a certain new and useful Improvement in Telephone-Locks, of which the following is a full, clear, and exact description, such as will enable others skilled in the art to which it appertains to make and use the same, reference being had to the accompanying drawings, forming part of this specification, in which—

Figure 1 is an elevation through the box or casing, said casing being shown in section. In this figure the parts are shown in full lines in their normal locked position. The heavy dotted lines indicate the positions of a deposited coin and the pivoted locking-dog after the coin has been deposited and before the slide-bar has been elevated, and the light dotted lines indicate the positions of the parts after the slide-bar has been elevated. Fig. 2 is a plan view, a portion of the casing being shown in section.

My invention relates to improvements in telephone-locks, my object being to provide a simple and efficient construction having but few parts.

To this end, and also to improve generally upon devices of the character indicated, my invention consists in the various matters hereinafter described and claimed.

Referring now more particularly to the drawings, 1 represents a portion of a telephone-box, which can be of any suitable construction, and 2 indicates the customary suspension-hook for the usual telephone-receiver 3. A box or casing 4 is secured to the wall or other support to extend at the side of the telephone-box and over the said suspension-hook, said casing containing the herein-after-described locking mechanism and being provided with a coin-raceway 5 and also with a horizontal slot 6 in its bottom wall, suitable guides 7 being properly related to the said slot to direct the slide-bar in its movements. Movable through said slot and between said guides is a substantially vertical slide-bar 8, whose lower end lies above the receiver's suspension-hook 2 and locks said hook in its lowermost position for well-un-

derstood purposes, said slide-bar being preferably provided with a slot 9, which receives a guide-pin 10, extending upon the casing. Pivoted above the slide-bar is a locking-dog 12, whose lower surface normally lies above the upper end 11 of the slide-bar in such position that said slide-bar is normally locked against upward movement, said locking-dog preferably being provided a projection 13, which is adapted to engage the edge of the slide-bar, and thus prevent the locking-dog from swinging beyond its proper position. The end of the lower wall 14 of the raceway 5 is spaced from the upper edge of the slide-bar, so that a coin-seat is formed between said parts, and in its side toward the raceway the slide-bar is provided with a recess 15, which when the slide-bar is in elevated position cooperates with the raceway to produce a coin-passage into the coin-receptacle 16. The upper portion of the edge of the slide-bar opposite the raceway is inclined inwardly and upwardly, as shown at 17, and the surface of the locking-dog with which said inclined portion of the slide-bar engages is cut away, as shown at 18, in order to permit the proper movement of the parts without throwing the locking-dog through an unduly large arc of a circle.

The parts normally lie in the positions indicated by full lines in Fig. 1, the receiver suspension-hook being locked in lowermost position in a manner which will be apparent. Upon the introduction of a coin or token into the raceway such coin falls into the seat between the end of the wall 14 and the end of the slide-bar, and as it falls into such position it engages the locking-dog and throws the same out of locking position. The slide-bar is now free to be moved, and as soon as the receiver is lifted from the suspension-hook the usual spring connected to said hook raises the same, and thus carries the slide-bar upwardly. In its upward movement the slide-bar throws the locking-dog into the position indicated by the light dotted lines and forces the coin backwardly along the raceway until the recess 15 reaches such position with relation to the raceway that the hereinbefore-mentioned passage into the coin-receptacle is 100

produced, when the coin falls through the passage into said receptacle. The parts remain in the positions shown by the light dotted lines until the receiver is again placed on the suspension-hook, when the slide-bar falls in a well-understood manner and the locking-dog swings downwardly and forwardly into locking position, undue movement of the dog toward such position being prevented by the engagement of the projection or finger 13 with the slide-bar. The locking-dog lies intermediate the slide-bar and the pivot pin or stop 19, thus effectually locking the slide-bar against upward movement until another coin is deposited.

I am aware that many minor changes in the construction, arrangement, and combination of the several parts of my device can be made and substituted for those herein shown and described without in the least departing from the nature and principle of my invention.

The locking-dog is pivoted at such a point with relation to the upper end of the slide-bar that there is less space between said bar end and the pivotal member than is the width of the operating-coin, whereby the movement of said coin toward said locking-dog is limited and there is no possibility of said coin falling over the end of the bar in such position that the bar cannot operate or the coin

be properly discharged into the coin-receptacle.

Having thus described my invention, what I claim as new, and desire to secure by Letters Patent, is—

In a mechanism of the character indicated, a substantially vertically movable locking-bar, a locking-dog pivoted above said bar and adapted to hang in the path of upward movement of said bar to prevent such movement thereof, and a coin-raceway wall spaced from one side of said bar a distance less than the width of an actuating-coin and adapted to direct a deposited coin against said dog and upon the top of said bar, whereby a coin-seat is produced between the end of said wall and the upper end of said bar, said bar having a cut-away portion upon its side toward said wall and below said coin-seat, whereby a deposited coin moves said locking-dog from locking position, seats upon said seat and falls therefrom upon upward movement of said bar; substantially as described.

In testimony whereof I hereunto affix my signature, in the presence of two witnesses, this 21st day of June, 1902.

WILLIAM H. SCOTT.
